3912

PATENTED MAR 15 1870

*John Tiebout's Design for Shutter Bar:**Fig:1.**Fig:2.**Witnesses.*

b. Wahler
John Tiebout

Inventor.

United States Patent Office.

JOHN TIEBOUT, OF NEW YORK, N. Y.

Design No. 3,912, dated March 15, 1870.

DESIGN FOR SHUTTER-BAR.

The Schedule referred to in these Letters Patent and making part of the same

To all whom it may concern:

Be it known that I, JOHN TIEBOUT, of the city, county, and State of New York, have invented a new and original Design for Shutter-Bar; and I do hereby declare the following to be a full, clear, and exact description thereof, which will enable those skilled in the art to make and use the same, reference being had to the accompanying drawing forming part of this specification, in which drawing—

Figure 1 shows my design in plan view.

Figure 2 is a longitudinal section.

My invention consists in the peculiar design of the shutter-bar and the fixed plates.

The fixed plates A A are of the shape shown in the drawing, placed parallel with each other.

The ends B B of the bar are circular, and of the

same outline, except where the free end is cut away to form the hook, and said ends are surmounted by buttons, C C, circular in form, and of the same dimensions with each other. The diameters of the buttons C C are less than the diameters of the rounded ends of the bar.

By my new design, I give a symmetrical appearance of the form shown to the shutter-bar at both ends.

I am aware that the shutter-bar, as an article of manufacture, is not new.

I claim the design above described for shutter-bar.

JOHN TIEBOUT.
